UNITED STATES PATENT OFFICE.

HUGO F. RIPKEN, OF MINNEAPOLIS, MINNESOTA, ASSIGNOR OF ONE-HALF TO CHARLES A. McCULLOCH, OF MINNEAPOLIS, MINNESOTA.

DRIFTING AND RELIEF VALVE.

1,280,848.

Specification of Letters Patent.

Patented Oct. 8, 1918.

Application filed March 23, 1918. Serial No. 224,198.

To all whom it may concern:

Be it known that I, Hugo F. RIPKEN, a citizen of the United States, residing at Minneapolis, in the county of Hennepin and State of Minnesota, have invented certain new and useful Improvements in Drifting and Relief Valves, of which the following is a specification.

My invention relates to improvements in 10 drifting and relief valves for reciprocating steam engines, and especially for those employed in railway locomotives using superheated steam.

The present invention is an improvement 15 to be applied in the drifting valve shown in my pending application for Letters Patent on drifting and relief valves, filed June 10, 1916, Serial No. 108,328.

It will be understood that when the throttle valve of an engine moving under steam pressure, is closed to cut off the steam supply from the cylinder the engine will drift for some time before it actually comes to rest. In thus drifting, the piston will continue to reciprocate under the inertia of the locomotive.

When, in an engine the live steam supply entering the cylinders is cut off, the pressure behind the advancing piston (during 20 the drifting) is reduced to a degree which tends to or does create a vacuum at that point. This causes an inrush of air through the usual cylinder cocks and also from the smoke box through the exhaust nozzle and 25 exhaust chamber when the piston valve in the steam chest has uncovered the port to the exhaust channel on that side.

In engines having superheating equipment the creation of a vacuum behind the 30 piston is very objectionable, the resulting inrush of air, gas and other foreign matter causing combustion and the destruction of the lubrication in the cylinder, thereby resulting in undue friction and excessive 35 wearing of parts.

The object of the present invention is to provide in my prior invention, means for positively controlling the movement of the valve piston and for controlling the pressure 40 sure above the piston, when the throttle is closed.

More particularly the invention consists in the construction, combination and arrangement of parts hereinafter described 45 and claimed.

In the accompanying drawings forming part of this specification,

Figure 1 is a vertical, longitudinal section through the middle of the cylinder and steam chest of a reciprocating engine with 50 my improved valve in elevation, and

Fig. 2 is a vertical section through the middle of the valve alone.

In the drawings, A represents the cylinder of a reciprocating engine, B the piston 55 working therein, and C the steam chest in which works a valve piston D, all of usual type.

The drifting valve which is the subject of this invention comprises a cylindrical 60 casing or valve body 2, the interior of which is open to communication with one end of the interior of the cylinder through the medium of the threaded nipple 3 at the lower extremity of the valve body, the interior 65 of which leads into a duct 4 extending around a bushing at one end of the steam chest to the cylinder port 5 on that side of the piston B.

The compressed air or steam in that end 70 of the cylinder will thus pass through the duct 4 into the lower part of the valve casing, under the valve, hereinafter described.

Leading from the top of the valve casing 75 2 to the main steam supply pipe or conduit E and communicating with the interior thereof is an auxiliary steam supply pipe 6 communicating with the interior in the top 80 of the casing 2, the casing being provided at one side, projecting laterally therefrom, with a live steam inlet 7, which is open to communication with the pipe 7a which is connected with a source of live steam supply such as the dome of the boiler. 85

Working within the valve casing 2 is a sliding hollow valve piston 8, having an inset bottom, forming an inverted cuplike lower portion. The upper portion of the piston is of enlarged diameter, forming at 90 the point where it joins the lower portion, a circular flat seat or shoulder 9, which seats on a co-operating shoulder 9a in the casing.

The piston may therefore be termed a differential piston as it has a top and bottom of different diameters and main and auxiliary bottom surface. A plurality of oblong ports 10 pierce the periphery of the upper portion of the piston, suitable piston rings to prevent leakage being provided above and 110

below the ports and immediately adjacent thereto.

A bushing 11 wherein the piston 8 slides, forms an inner cylindrical wall for an annular groove cast in the wall of the casing, thereby forming the annular walled in chamber portion of the inlet 7, the inlet being open to communication with the interior of the supply pipe 7^a. This inner wall of the 10 inlet chamber portion is pierced by a circumferential row of ports 13, which are arranged to register with the ports 10 when the piston 8 is slid upward against the shoulder 14 in the casing.

15 Leading downwardly from the annular chamber portion of the inlet, in the casing wall and opening into the interior of the casing at a point above the shoulder 9^a (whereon the piston normally rests) through 20 the port 15 is a duct 15^a, the port being guarded against leakage by suitable piston rings in the piston.

It will be noted (Fig. 2) that the ports 10 and 13 are adequately protected by piston 25 rings to guard against undue leakage of steam from the pipe 8.

Opposite the port 15, piercing the wall of the casing at a point in the shoulder 9^a is a vent 16 which acts as an exhaust and may 30 be open to the atmosphere, or be connected with the exhaust chamber as shown in Fig. 1.

In operation, when the throttle valve, not shown is closed, the pressure in the conduit immediately thereafter falls or is reduced, 35 while the piston B (Fig. 1) will travel, (while the engine is drifting), to the right, compressing the gases before it, and producing a back pressure in the cylinder, in the port 5, and in the duct 4. This back 40 pressure is communicated to the bottom of the valve piston 8, causing it to be lifted from its seat in the casing and slide upwardly until it abuts against the shoulder 14. When in this position, as hereinbefore 45 stated, the ports 10 and 13 are in perfect register, thereby establishing communication between the interior of the pipe 7^a and the interior of the casing.

Live steam from pipe 7^a will now pass (as 50 indicated by the arrows Fig. 1) through the inlet into the casing 2 above the valve piston and through the medium of pipe 6 and conduit E enter the steam chest and cylinder, where it will prevent any vacuum forming 55 tendency behind the piston.

My hereinbefore mentioned prior invention, operated, generally up to this point, as above described, but I have found by experiment that the pressure in the conduit 60 (when the throttle is closed) which is counteracted only by the back pressure generated in the cylinder and the friction of the packing rings (on the valve piston) and which, in my prior invention was solely relied upon 65 to maintain the valve piston in operating

position, was not adequate, to prevent a fluctuating movement of the valve piston which caused the supply of steam admitted through the inlet 7 to be reduced to such a degree as to render the pressure in the cylinder inadequate for drifting.

70 To prevent a fluctuating movement of the valve, I provide the duct 15^a having a port 15 whereby live steam is conducted into an annular cavity between the piston and the 75 casing wherein it will press upwardly against auxiliary piston surface, thereby opposing and in part counterbalancing excessive conduit pressure on the top of the valve piston, thereby controlling movement 80 of the piston.

As the valve piston 8 is automatically raised, (by pressure generated in the cylinder), it uncovers the port 15 to admit live steam to the annular cavity formed between 85 the seat 9 and its coöperating shoulder 9^a in the casing (when the valve piston is moved) the steam pressure in the cavity serving to regulate the pressure which causes the downward movement of the piston as 90 will be hereinafter explained.

The vent 16 admits air to the cavity to prevent the creation of the vacuum therein (when the valve piston is raised) which would otherwise tend to oppose the back 95 pressure generated in the cylinder. It also acts as a restricted outlet for the inrushing steam, the vent 16 being appreciably smaller than the inlet port 15, resulting in back pressure in the cavity, whereby the piston is controlled to descend only when there is excessive steam pressure above it, which occurs when the engine is drifting very slowly or actually comes to rest.

100 When the engine comes to rest the valve piston descends, covering the ports 10 to cut off the live steam supply and then covering the port 15 from which point it will slowly descend, riding on the air or steam pocketed in the cavity which is now expelled through 110 the restricted vent 16 by the descending piston, whereafter the piston valve comes to rest on its seat.

115 While I prefer the particular construction shown in the drawings, I wish it understood that many variations in the general structure may be made without departing from the general principle underlying my invention.

I claim:

120 1. In a reciprocating engine, the combination with the cylinder and steam chest, of a drifting valve comprising an outer casing open to communication with the cylinder at one end and communicating with the steam chest at the other end, an annular ported 125 steam inlet chamber in the casing to admit live steam, a ported slideable valve piston in the casing having a shoulder and adapted to register with its ports, the ports in said an- 130

- nular chamber but normally covering the latter and actuatable by the pressure in the cylinder when the engine is drifting and the main steam supply is cut off, and a duct in 5 the casing open to communication with said annular chamber at one end and opening at its other end against the sliding face of the ported valve piston above said shoulder and rendered operative, when the valve piston 10 is actuated to uncover the ports in said annular chamber and said opening of said duct to admit live steam into contact with a part of the piston below said shoulder to control its movement.
- 15 2. In a reciprocating engine, the combination with the cylinder and steam chest, of a drifting valve open to communication with the cylinder at one end and with the steam chest at the other end, said drifting valve 20 comprising a ported outer casing having a live steam inlet to admit live steam, a ported differential valve piston in the casing normally covering said live steam inlet to hold the interior of the casing above the piston 25 closed to communication with the steam chest and actuatable by pressure in the cylinder when the engine is drifting and the main steam supply is cut off, and having a main and auxiliary pressure receiving bottom sur- 30 face and a duct in the casing open to communication with said live steam inlet at one end and closed by the piston to communication with said auxiliary pressure receiving bottom surface at the other end, but opened 35 to communicate therewith when said differential valve piston is actuated for the purpose set forth.
3. In a reciprocating engine, the combination with the cylinder and steam chest, of a 40 drifting valve open to communication with the cylinder at one end and communicating with the steam chest at the other end, said drifting valve comprising an outer casing having a differential bore and an annular 45 ported live steam inlet to admit live steam, a valve piston in the bore of the casing actuatable by pressure in the cylinder when the engine is drifting and the main steam supply is cut off and normally holding the in- 50 terior of the casing above the piston closed to communication with said annular ported live steam inlet and a duct open to communication with the annular live steam inlet, and having a port adjacent the point of dif- 55 ferentiation in said bore and normally covered by the valve piston and rendered effective when the valve piston is actuated to admit live steam into the casing above the piston and said port is uncovered to admit live
- steam to completely surround a part of said 60 valve piston to exert an upward pressure thereon.
4. In a reciprocating engine, the combination with the cylinder and steam chest, of a drifting valve, comprising a valve casing 65 open to communication with the cylinder at one end and the steam chest at the other end, said valve casing having a live steam inlet and an internal shoulder, a piston having a peripheral seat adapted to engage said shoulder and normally in engagement therewith covering said live steam inlet, said piston being actuatable to disengage said shoulder and uncover said live steam inlet by the pressure in the cylinder when the engine is 75 drifting and the main steam supply is cut off, a duct in the casing open to communication with said live steam inlet and the interior of the valve casing adjacent and above said shoulder, and a vent piercing said shoulder and opening against said peripheral seat of the piston when the latter is in engagement with said shoulder whereby when the piston is actuated to uncover said live steam inlet to admit live steam into the interior of 80 the valve casing above the piston steam admitted through the duct to the underside of said peripheral seat to exert pressure thereon may escape, said vent and duct differentiating in size for the purpose set forth. 85
5. In a reciprocating engine, the combination with the cylinder and steam chest, of a drifting valve comprising a casing open to communication with the cylinder at one end and the steam chest at the other end, a movable ported device fitted slidably in the casing and dividing the interior thereof to prevent communication between said ends and actuatable by the pressure in the cylinder when the engine is drifting and the main steam supply is cut off, a ported live steam inlet in the casing in the path of said ported movable device and adapted to register therewith when the latter is moved, a duct open to communication at one end with said live steam inlet, and means in the casing and said movable device cooperating when the latter is moved to further divide the interior of the casing and to uncover the other end of said duct into communication with 100 the interior of the casing for the purpose set forth. 105
